COLLAPSIBLE TABLE OR THE LIKE

Charles Golden, Brooklyn, N. Y.

Application August 25, 1934, Serial No. 741,384

2 Claims. (Cl. 311—78)

My invention relates to a new and improved collapsible table.

One of the objects of my invention is to provide a table which can be used as a card-table, and for various other purposes.

One of the objects of my invention is to provide a collapsible table of simple and improved construction, which can be collapsed into very small space, and which will be strong and durable when the table is in the collapsed and in the extended position.

Another object of my invention is to provide a table of this type having a rigid and collapsible frame, and a top which is made of flexible material, which can be rolled up. However said top may be made of wood or metal, either rigid or resilient, and a top made of material such as wood or the like, can be made of a plurality of parts, either separate, or connected by hinges, etc.

Other objects of my invention will be set forth in the following description and drawings, which illustrate a preferred embodiment thereof.

Fig. 1 is a bottom view of the improved device, the legs having been turned until they are substantially parallel with the top of the table.

Fig. 2 is a bottom view which is generally similar to Fig. 1, save that Fig. 2 shows the frame partially collapsed, and Fig. 1 shows the frame fully extended.

Fig. 3 is a detailed perspective view, showing the joint between a pair of end frame members.

Fig. 4 is a transverse sectional view of the table in its fully extended position.

Fig. 5 is a bottom view of the improved device, showing the frame members in their fully collapsed position.

Fig. 6 is a sectional view on the line 6—6 of Fig. 5.

Fig. 7 is an end elevation of the improved device, showing the same in its fully collapsed condition, with the top of the table in its rolled-up position.

As shown in Fig. 1, the frame of the table comprises two side members 1, which are made of wood or any other suitable material. These side members 1 have legs 2 pivotally connected thereto by means of pivot members 6, and said frame members 1 have additional legs 3 turnably connected thereto, by means of pivot members 7. When the legs are turned inwardly, the legs 2 are located below the legs 3, and in contact with said legs 3. As shown in Fig. 1, the pivots 7 are above pivots 6.

The two ends of the frame respectively include

end frame members 14, 15 and end frame members 16 and 17.

The end frame members 14 and 15 are connected by a hinge 23, so that said end members 14 and 15 can be moved inwardly from the position shown in Fig. 1, a partial inward movement being shown in Fig. 2. The end frame members 16 and 17 are connected by a similar hinge 23. When the end frame members 14 and 15 are aligned, their adjacent ends abut each other. The frame member 14 is provided with a projection 18, and this fits into a recess 20 of the frame member 15, when said frame members 14 and 15 are aligned with each other. The end frame member 16 is also provided with a projection 18a, which fits into a recess 21 of the frame member 17, when said frame members 16 and 17 are aligned with each other. As shown in Fig. 3, the height of the recess 20 is less than the height of the frame member 15, so that the projection 18 forms a tongue which fits quite snugly in the recess 20, thus preventing any relative movement between the frame members 14 and 15, when said frame members are in the aligned position shown in Fig. 1, save for the inward movement of said frame members 14 and 15 which is illustrated in Fig. 2.

The frame members 14 and 15 are generally identical in construction and operation with the frame members 16 and 17.

Each of the end frame members 14, 15, 16 and 17, is connected to the corresponding side frame member 1, by means of a hinge 24. When the parts are in the position shown in Fig. 1, the ends of said end frame members abut the corresponding edges of the side frame members 1.

As shown in Fig. 4, each of the legs of the table is associated with a brace 4, each brace being pivotally connected to a frame member 1, by means of an arm or bracket 5. Said member 5 is made of any suitable metal, and it is suitably connected to the frame member 1.

Each said metal brace 4 is provided with a slot 32. Each of the legs is provided with a headed pin 31, whose shank can slide in said slot 32. The shank of each said pin 31 slides in the slots 32 with sufficient friction, so that said braces serve to hold the legs of the table in the extended position which is shown in Fig. 4. Likewise, the ends of said slots 32 can be provided with enlargements, so as to detachably engage the shanks of pins 31, it being noted that this detail of construction is old and well-known.

In order to collapse the table, the end frame members 14, 15, and 16 and 17, are pushed in-

wardly, as illustrated in Fig. 2. Before this is done, the legs are also pushed inwardly, so that they occupy the position shown in Fig. 2.

When the frame is fully collapsed, the adjacent edges of the side frame members 1 abut each other. The projection 18 is then located in recess 21, and projection 18a is located in recess 20.

The top 8 of the table is made of any suitable flexible material, such as water-proof cloth or the like, and the top of the table also has an inside liner 9, which is made of any flexible material.

As shown in Fig. 1, the side edges of the top 8 and of liner 9 are inturned, so as to provide in-turned portions 11a, and said in-turned portions 15 11a are connected by means of stitches, so as to form pockets 11. Reinforcing slats 10 have their ends located and held in said pockets 11. These slats are made of any suitable rigid or flexible material, such as bendable or resilient wood or 20 metal, and since they are parallel to the frame members 1, said slats 10 can be designated as longitudinal slats. An additional reinforcing member 16a, made of wood or other suitable material, is pivotally connected at 22 to the central 25 slat 10. When the device is in the extended position, the member 16a is located as shown in Fig. 1, and perpendicular to the members 10. In such position, the ends of the reinforcing member 16a, substantially abuts the edges of the frame members 1.

When the device is to be collapsed, the member 16a is turned, until it is aligned with the central slat 10. The width of the member 16a is preferably a little less than that of the central 35 slat 10.

This construction provides a strong and rigid table when the device is extended, while permitting the ready collapse of the table into a very small space.

40 When the device has been fully collapsed, this being the position which is generally shown in Fig. 5 and Fig. 6, the legs 3 are located between the legs 2 and the end frame members. These parts may closely abut each other, in order to increase the strength of the device, when the frame has been fully collapsed.

The flexible members 8 and 9 can then be bent or rolled wholly or partially around the collapsed frame, this being illustrated in Fig. 7.

50 The longitudinal edges of the members 8 and 9 are connected to the tops of the frame members 1, by any suitable fastening members. These fastening members 12 and 13 are clearly shown in Fig. 1 and Fig. 7.

55 Since the top of the table has its ends free or disconnected from the end frame members, the collapse of the rigid frame parts of the device to the position shown in Fig. 5, permits the adjacent part of the top of the table to assume the position shown in Figs. 5-7 inclusive.

In this position the top of the table has a general U-shape and only one of the reinforcing members 10 is located directly adjacent the collapsed frame. The parts of the frame may be 65 made of wood, metal or any other suitable material.

While I have referred to a collapsible table having legs, the invention is not necessarily limited to the use of legs, and I do not wish to 70 limit the construction disclosed herein, for any specific purpose.

Likewise, while I have disclosed a frame which has a general rectangular shape when the same

is extended, I do not wish to be limited to this particular shape.

By connecting the top of the table, only to some of the frame members, such as the frame members 1, it is possible to collapse the device while 5 keeping the top thereof wholly external to the collapsed frame, as shown in Fig. 6.

It is clear that the permanent fastening members 12 and 13 could be replaced by detachable fastening members if desired. Likewise the ends 10 of the top of the table could be connected to the end frame members by means of detachable fastening devices, if desired.

While I have shown a plurality of reinforcing members 10, it would not be departing from the 15 invention if I used only a single reinforcing member 10 to which the second reinforcing member 16a is turnably connected.

Referring to Fig. 6, this shows the end frame members substantially parallel to each other and 20 substantially parallel to side frame members 1. Likewise, Fig. 1 shows that hinges 24 are above the pivots 6 and 7. Fig. 6 shows that when the table is collapsed, the legs 2 and 3 are arranged in superposed pairs which are superposed relative to the end frame members. The height of the side frame members is substantially equal to the combined heights of the legs and end frame members.

I have shown a preferred embodiment of my 30 invention, but it is clear that numerous changes and omissions can be made without departing from its spirit.

I claim:

1. A collapsible table, comprising side frame members, legs pivotally connected to the inner sides of said side frame members, said legs being pivotally connected to their respective side frame members at points which are spaced unequally from the bottom edges of said side frame members, so that said legs can be turned until they are substantially parallel to each other and substantially parallel to said side frame members, end frame members turnably connected to each other and connected to said side frame members above the pivots of said legs, said end frame members being turnable inwardly so that the table can be collapsed with said legs arranged in superposed pairs, each pair of legs and a pair of end frame members being then in superposed relation.

2. A collapsible table, comprising side frame members, legs pivotally connected to the inner sides of said side frame members, said legs being pivotally connected to their respective side frame members at points which are spaced unequally from the bottom edges of said side frame members, so that said legs can be turned until they are substantially parallel to each other and substantially parallel to said side frame members, end frame members turnably connected to each other and connected to said side frame members above the pivots of said legs, said end frame members being turnable inwardly so that the table can be collapsed with said legs arranged in superposed pairs, each pair of legs and a pair of end frame members being then in superposed relation, the height of the side members being at least equal to the heights of said legs and to the height of an end frame member, when the table 70 is collapsed.

CHARLES GOLDEN.
